Fig. 5.

Fig. 1 is a plan view of a full panel of plastic sheet material embodying the new design;

Fig. 2 is an enlarged plan view of the embossed design appearing at the upper left of Fig. 1;

Fig. 3 is an enlarged plan view of the embossed design appearing at the upper right of Fig. 1;

Fig. 4 is an enlarged plan view of the embossed design appearing in the center of the panel;

Fig. 4a is a cross-sectional view taken along the line 4a-4a of Fig. 4, illustrating the contours of the embossing;

Fig. 5 is a plan view on an enlarged scale illustrating the design appearing at the lower left of Fig. 1;

Fig. 6 is a plan view on an enlarged scale illustrating the design at the lower right of Fig. 1.

The pictorial portions of the panel design are formed by embossing ridges and grooves as particularly shown in Fig. 4a upon a plain background, giving a raised or contoured effect to the decorated portions.

I claim:

The ornamental design for a panel of plastic sheet material or similar article, substantially as shown and described.
